BARBECUE

Ralph A. Ford, Westtown, N.Y., assignor to Valley
Cast Concrete, Inc., Westtown, N.Y.

Filed Aug. 12, 1970, Ser. No. 24,462

Term of patent 14 years

Int. Cl. D7—02

U.S. Cl. D81—10

FIG. 1 is a perspective view of a barbecue embodying the design.

FIG. 2 is a rear view of the barbecue of FIG. 1.

FIG. 3 is a sectional view of the barbecue of FIG. 1, taken along the line 3—3, looking in the direction of the arrows. The side opposite to the one shown in FIG. 1 is a mirror image thereof.

I claim:

The ornamental design for a barbecue, as shown and described.
